UNITED STATES PATENT OFFICE.

JOHN LEIPER, OF NEW YORK MILLS, NEW YORK, ASSIGNOR TO NEW YORK MILLS CORPORATION, OF NEW YORK MILLS, NEW YORK.

DESIGN FOR COTTON PIECE GOODS.

Application filed June 5, 1922. Serial No. 2,539. Term of patent 14 years.

To all whom it may concern:

Be it known that I, JOHN LEIPER, a citizen of the United States of America, residing in New York Mills, county of Oneida, and State of New York, have invented a new, original, and ornamental Design for Cotton Piece Goods, of which the following is a specification, reference being had to the accompanying drawing forming part thereof.

The fabric consists of raised tufted or fluffy sections of substantial height, subdivided both longitudinally and transversely, the contrasting base of the fabric being prominently visible.

I claim:

The ornamental design for cotton piece goods as shown.

JOHN LEIPER.
